UNITED STATES PATENT OFFICE.

WILLIAM H. GAGGINS, OF PHILADELPHIA, PENNSYLVANIA.

SHOE-REST.

1,110,386.

Specification of Letters Patent. Patented Sept. 15, 1914.

Original application filed August 8, 1913, Serial No. 783,665. Divided and this application filed October 14, 1913. Serial No. 795,048.

To all whom it may concern:

Be it known that I, WILLIAM H. GAGGINS, a citizen of the United States, residing at Philadelphia, county of Philadelphia, and 5 State of Pennsylvania, have invented a new and useful Improvement in Shoe-Rests, of which the following is a full, clear, and exact description, reference being had to the accompanying drawings, which form a part 10 of this specification.

The object of my invention is to provide a new and improved shoe rest adapted for use in the polishing of shoes.

In such a device, whether the shoe is polished by means of a brush or cloth; or by 15 a cloth coöperating with guides, as in an application filed by me August 8, 1913, Serial No. 783,665; it is important that the shoe should not slip off the rest and that the 20 rest should be capable of being turned at any angle to its support so as to allow the brush or cloth to be brought into frictional contact with every part of the surface of the shoe that is to be polished, while at the same 25 time the shoe will be maintained in fixed relation with the rest.

The more specific object of my invention is to provide a foot rest meeting these requirements.

30 A preferred embodiment of the invention is shown in the accompanying drawings, in which Figure 1 is a plan view of my improved shoe rest; Fig. 2 is a side elevation; and Fig. 3 is a section on the line 3—3 of 35 Fig. 1.

The base plate or support *a* is intended to be secured, preferably by screws, to any suitable platform. Projecting upward from the base is a hollow support or pocket *b* 40 whose side wall at its upper end curves inward toward a central opening in the top of the pocket. This affords a convex spherical-shaped surface for the support of a cup *c* whose inner or lower surface is of concave 45 spherical shape so as to suitably engage the pocket *b*. Secured to and depending from the center of the cup *c* is a rivet *d* to the lower end of which is secured a plate *e* which is within the pocket *b* and having a 50 peripheral flange engaging the inner surface of said pocket. The cup *c* depends from a plate *f* constituting the foot rest proper. The flanged plate *e* is preferably 55 of thin metal so as to have a degree of elasticity.

The shoe plate *f* is adapted to directly support that part of the shoe extending in front of the heel. Around the outer margin of the plate the same is flanged at *g*, upwardly, the upper edge of the flange projecting above the level of the top of the adjacent part of the plate *f*. Between the flange *g* and the body of the plate *f* is a groove *h*. This groove is wider at its rear end than along the remainder of its length, 60 and the flange is so curved as to form guides *i* for a cloth, which may be passed under the rear of the shoe plate and its opposite ends brought upward over the guides *i* and in sliding contact with the shank or instep 65 portion of the shoe. 70

When the shoe is placed on the shoe plate *f*, the upper edge of the flange *g* engages the sole of the foot so firmly that, with the slight downward pressure which will naturally be applied by the user, there will be no tendency for the shoe to slip upon the shoe plate. The supporting means described virtually act as a universal joint and enable 75 the foot to assume any desired angle so that the position of the foot may be altered from time to time without altering the position of the shoe relatively to the shoe plate. 80

Having now fully described my invention, what I claim and desire to protect by Letters 85 Patent is:

1. A shoe rest comprising a hollow support having a rounded outer surface, a plate for supporting the shoe, and a cup and a flanged plate depending from the shoe plate, 90 said cup having a rounded inner surface slidable upon the rounded outer surface of the support, and said flanged plate extending within the hollow support and adapted to engage the latter's inner surface. 95

2. A shoe rest comprising a hollow support open at the top and having a rounded outer surface adjacent to the top, a plate for supporting the shoe, a cup depending from the shoe plate having a rounded inner surface resting upon the rounded outer surface of the support, and a member within the hollow support connected with the shoe plate through the open top of the hollow support and adapted to engage the latter's inner surface. 100

3. A shoe rest comprising a hollow support, a plate for supporting the shoe, a cup depending from the shoe plate, said cup located outside the hollow support and mov- 105

able relatively thereto, a plate within the hollow support connected with the shoe plate, said inner plate being elastic and flanged to contact with the inner surface of the hollow support.

4. A shoe rest comprising a hollow support open at the top and having a rounded contour adjacent to the top, a plate for supporting the shoe, a cup depending from the shoe having a rounded inner surface slidably resting upon the rounded outer surface of the support, a plate within the hollow support connected with the shoe plate through the open top of the hollow support, the last named plate having flanges adapted to engage the rounded inner surface of the hollow support.

5. A shoe rest comprising a support having a part thereof presenting a spherically curved surface, a plate for supporting the shoe, and means depending from the plate

having a part thereof presenting a spherically curved surface conforming to the spherically curved surface of the support and arranged to have a limited sliding movement thereupon in every direction. 25

6. A shoe rest comprising a support having an open top and spherically curved inner and outer surfaces beneath such opening, a plate for supporting the shoe, and means 30 depending from the plate having parts thereof conforming respectively to the spherically curved inner and outer surfaces of the support and adapted to slide thereupon.

In testimony of which invention, I have 35 hereunto set my hand, at Philadelphia, on this tenth day of October, 1913.

WILLIAM H. GAGGINS.
